UNITED STATES PATENT OFFICE.

FERDINAND MINCK, OF DANBURY, CONNECTICUT.

WRENCH AND PIPE-CUTTER.

No. 805,927.

Specification of Letters Patent.

Patented Nov. 28, 1905.

Application filed August 22, 1905. Serial No. 275,256.

To all whom it may concern:

Be it known that I, FERDINAND MINCK, a citizen of the United States, residing at Danbury, county of Fairfield, State of Connecticut, have invented a new and useful Wrench and Pipe-Cutter, of which the following is a specification.

This invention has for its object to provide a simple and inexpensive hand-tool which shall be easily convertible into either a wrench or a pipe-cutter.

With this end in view I have devised the simple and novel structure of which the following description in connection with the accompanying drawings is a specification, reference characters being used to indicate the several parts.

Figure 1 is an elevation illustrating my novel tool in use as a pipe-cutter; Fig. 2, a top plan view corresponding with Fig. 1; Fig. 3, a side view corresponding with Fig. 1 with the face-plate removed and the yoke and locking-screw bracket in section, and Fig. 4 is an elevation of a movable wrench-jaw and slide detached.

10 denotes the body and 11 the fixed jaw which is formed integral therewith.

12 denotes a sliding wrench-jaw and 13 a sliding cutting-jaw, each of which is formed integral with a slide 14, adapted to slide in a way 15, formed in the body, the slides being interchangeable. The body is also preferably provided at the center of the way with a transverse rib 16, and the slides are provided with grooves 17, which receive the rib. 18 denotes the face-plate, which is secured to the body by screws 19. The fixed jaw is provided with a socket 20, in which a cutting-disk 21 may be pivoted, as upon a screw-stud 22, when the tool is to be used as a pipe-cutter. When the tool is to be used as a wrench, this disk is of course removed. The cutting-jaw is provided with a recess 23, in which two cutting-disks 21 are pivoted. For ordinary use as a wrench it is contemplated to remove the sliding cutting-jaw 13 and replace it with the sliding wrench-jaw 12. If preferred, however, the cutting-disks may be removed from the cutting-jaw, and that jaw may be used as a wrench-jaw, the shape of both the fixed and sliding jaws being wholly immaterial so far as the principle of the invention is concerned.

24 denotes the handle, which is pivoted in a recess 25 at the rear end of the body, ordinarily upon a screw-bolt 26, which passes

through the handle, body, and face-plate and is shown as provided with a wing-nut 27 for convenience in removal. The forward end of the handle is adapted to suitably engage the slide, as at 28, so that oscillation of the handle will reciprocate the slide with which it is engaged and carry the movable jaw into operative position, in which position it is retained by pressure upon the handle. 65

When the tool is to be used as a pipe-cutter, a locking-screw 29 is provided which bears against the handle to lock the handle and with it the sliding cutting-jaw in operative position. This screw is provided with a finger-piece 30 for convenience in operation. As the cutting operation proceeds the operator turns this screw inward against the handle, and thereby feeds the cutting-jaw forward. The locking-screw is carried by a removable 75 bracket 31, which is secured to the body by a screw 32. In order to give additional rigidity to this bracket, a yoke 33 is provided, which incloses the bracket and locks it rigidly in place. This bracket is shown as locked to 80 the body by means of screw-bolt 26. The yoke straddles the body and the screw-bolt passes through both arms of the yoke, as is clearly shown. When the tool is used as a wrench, a shorter screw-bolt may be used. 85

The operation of the tool as a pipe-cutter will be readily understood from Figs. 1, 2, and 3, in which I have indicated a pipe being operated upon by dotted lines in connection with the description already given. When 90 the tool is used as a wrench, a sliding wrench-jaw may be substituted for the sliding cutting-jaw and the locking-screw, bracket, and yoke removed.

Having thus described my invention, I 95 claim—

1. In a tool of the character described, a body portion having a fixed jaw, a movable jaw having a slidable engagement with said body portion, a handle pivoted in said body 100 and having means adapted to engage with and move the slidable jaw, a bracket carried by the body portion, and means carried by the said bracket adapted to retain the handle in a position whereby the handle will hold 105 the movable jaw in an operative position.

2. In a tool of the character described, a body portion provided with a fixed jaw, a movable jaw having a slidable engagement with the said body portion, a handle pivoted to said body portion, said handle having a portion adapted to engage with and move 110

the movable jaw, a bracket provided with means for limiting the movement of said handle to retain the movable jaw in operative position, and means for detachably securing 5 said bracket to the body portion.

3. A tool of the character described comprising a body having a transverse way and a fixed jaw, a movable jaw adapted to be slid- 10 ily mounted in said transverse way, a han- dle pivoted in the body and engaging with said movable jaw, a bracket detachably se- cured to the body and a locking-screw in said bracket adapted to bear against the handle to lock the movable jaw in operative position.

4. In a tool of the character described the combination with a body having a fixed jaw provided with a recess, said body being pro- 15 vided with a transverse way, a movable jaw slidingly mounted in said transverse way, a handle pivoted to the body and adapted to engage with the said movable jaw, for the purpose set forth, a bracket, a locking-screw

in said bracket adapted to engage the handle to lock the movable jaw in operative position, and means for detachably securing 25 said bracket to the body portion.

5. In a tool of the character described the combination with a body having a fixed jaw provided with a recess, a movable jaw slid- 30 ily mounted in said body, said movable jaw being provided with recesses, a handle pivoted to the body and adapted to engage with the movable jaw, a detachable bracket, a locking-screw in said bracket adapted to 35 lock the movable jaw in operative position and a yoke inclosing the bracket and secured to the body for retaining the bracket rigidly in place.

In testimony whereof I affix my signature 40 in presence of two witnesses.

FERDINAND MINCK.
